Int. Cl. D6—06

U.S. Cl. D6—3

FIG. 1 is a rear perspective view of an invertible chair and bookcase combination showing our design in position for use as a chair and bookcase;

FIG. 2 is a perspective view thereof wherein the cushion elements have been omitted, the leg members have been attached and the unit is in inverted position for use as a table and bookcase;

FIG. 3 is a side elevational view showing the side not disclosed in FIG. 2;

FIG. 4 is an end elevational view taken from the left in FIG. 2; and

FIG. 5 is a front perspective view of the combination shown in FIG. 1.

We claim:

The ornamental design for an invertible chair and bookcase combination, substantially as shown.
